SELECTOR MECHANISM FOR ELECTRICAL
ROLL CALL OR VOTING APPARATUS

Charles F. Thompson, Dumbarton, Va.

Application June 3, 1936, Serial No. 83,334

10 Claims. (Cl. 200—92)

My invention relates broadly to electrical roll-call or voting systems, such as are used by legislative and other deliberative bodies, and more particularly to an improved construction and system of operation for a commutator device adapted for actuating high speed vote recording and vote counting devices.

In the past, commutator devices for voting systems were capable of recording and counting only one vote at a time and hence required an unusually long period of time to operate, and they were not designed for continuous totalization, and therefore could not cause repeated totals to be shown to the members while they were voting.

In this, and other copending applications of the present series of applications, a new principle is disclosed for operating vote recording mechanism at high speed, which consists of dividing the membership into small divisions so that one vote from each division may be simultaneously recorded, instead of one vote at a time, and so that one vote from each division may be simultaneously stored for counting, instead of counting one vote at a time. The system of my invention provides for continuous totalization so that members or the presiding officer, or both, may be able to follow the trend of the voting as they do under the oral roll call, and so be in position to make or receive appropriate motions, and to save much valuable time.

Reference is made to the following copending applications for a more complete understanding of the relation of the commutator device of this invention with respect to the system in which it is adapted for use:

Serial No. 77,039, filed April 29, 1936, Electrical roll-call or voting apparatus.

Serial No. 77,839, filed May 4, 1936, Method and apparatus for electrically recording votes.

Serial No. 87,273, filed June 25, 1936, Recorder mechanism for electrical roll call or voting apparatus.

Serial No. 93,684, filed July 31, 1936, Visual indicator mechanism for electrical roll call or voting apparatus.

The present invention is directed to a system of operation for and a construction of commutator used to divide the membership into groups and accomplish the above results, and because this device operates upon new principles and performs new and varied functions, it will hereafter be referred to as the selector.

Among the objects of this invention are, therefore:

To provide a selector capable of causing a recording machine to record a plurality of votes simultaneously.

To provide a selector capable of causing a vote counting machine to store a plurality of votes simultaneously in several divisions, and then register the grand totals of the divisions.

To provide a selector capable of being operated for one cycle of operation when a single totalization or a single record is required; and capable also of being continuously operated for as long a period of time as may be desired, in order to cause the vote counting mechanism to register repeated totals while the members are voting.

To provide a selector with air dielectric between operating contactors, in order to overcome wear and carbonization of solid dielectric material and consequential breakdown of commutator.

To provide a selector with intermediate contactors, placed between operating contactors, for the purpose of permitting proper use of condensers in eliminating sparking.

I attain the above objects by mechanism illustrated in the accompanying drawings, in which—

Fig. 1 is a top sectional view of my selector on lines 1—1 of Fig. 4.

Fig. 2 shows a brake or stopping mechanism for arresting rotation of the selector driving motor as soon as current is disconnected therefrom.

Fig. 3 discloses a form of brush or wiper used with my selector.

Fig. 4 is a vertical sectional view of my selector on lines 4—4 of Fig. 1.

Fig. 5 shows a preferred method of tie-rod assembly used in my selector.

Fig. 6 discloses the circuits for recording the vote and actuating the vote storing mechanism of the counting devices, and also shows the spark elimination means for these circuits.

Fig. 7 illustrates the circuits for feeding the record card through the recorder, and spark elimination means for these circuits.

Fig. 8 shows the circuits for operating the selector driving motor and the circuits controlling the high speed vote counting mechanism, and spark elimination means for these circuits.

Fig. 9 illustrates a method of constructing my selector with divided rings instead of solid rings.

Fig. 10 is a diagram illustrating the sequence of action in one operating cycle of the selector.

Similar numerals refer to similar parts throughout the several views.

My selector consists of a base casting 11, supporting a series of insulating rings, such as shown at 12, each properly recessed to receive a plurality

of contactors, such as shown at 13 and 14. Rings, such as 12, may be made in the form of complete circles, or they may be composed of ring-sections, such as shown in Fig. 9, which would preferably be assembled in overlapping or brick-wall fashion. A top plate, 15, is placed on top of the rings 12.

The assembly of top plate 15 and rings 12, on casting 11, is accomplished by a series of tie-rods, such as shown at 16. These tie-rods may be screwed into casting 11, but I prefer to hold them therein by the method shown in Fig. 5, wherein a set-screw 17 enters notch 18. This construction prevents tie-rods from twisting during assembly, and also permits them to be easily removed for contactor replacement. The top ends of tie-rods 16 are threaded, and equipped with cap-nuts 19, so the entire assembly may be drawn together in the form of a rigid unit. Tie-rods 16 pass through holes in contactors 14, but they cannot touch the contactors as they are much smaller than the holes, and both tie-rods and contactors are immovable.

In the center of top plate 15 is a bearing projection 20, and in the center of casting 11 is a bearing projection 21. Journaled in bearings 20 and 21 is the main shaft 22, preferably of square cross-section between the journals. Recessed into shaft 22 and fastened securely thereto, are several arms, such as 23 and 24, which in turn supports the wiper rack 25. The rack 25 is made of insulating material, and fastened thereto by screws such as 26, and square nuts such as 27, are a series of wipers such as 28.

Wipers 28 are of U-shaped construction, so as to connect two adjacent rings of contactors together. It will be seen that the wipers 28 are composed of two individual members, 29 and 30, each having bent-up ears on the contacting portions. It will also be seen that one end of wiper 28 is of narrow width, 28a, and the other end, 28b, is considerably wider. Wiper end 28a is designed to secure precise timing of circuits, and wiper end 28b is designed to overlap two contactors. As shown in Fig. 3, an elongated hole 31, is used for attaching wipers 28 to rack 25, thus providing a means for aligning all wipers, and if desired to give a lag or lead to the wiper controlling the feeding of the record card through the recorder. The arrangement of wipers described provides nine vote recording circuits in divisions A, B and C; and four control circuits, E, F, G and H, for other functions.

Casting 11 is equipped with bolt holes 32 for mounting the selector. Projection 20 of top plate 15 is furnished with a threaded shoulder 33, designed to fit a hole 34 in selector cover 35. Selector cover 35 is adapted to fit over shoulder 33 on casting 11, and to be held in place by the threaded cap 38. The cables of wires from all contactors such as 13 and 14, pass inside of cover 35, through holes such as 39, to the interior of casting base 11, and then on to various other units. The selector is therefore protected from dust and unfavorable atmospherical conditions.

Attached to the main shaft 22 is the worm gear 40, which is engagement with worm 41 on motor shaft 42 of motor 43. Operation of motor 43 thus rotates wipers 28 at appropriate speed. The selector is equipped with a device for quickly arresting the rotation of motor 43 when said motor's operating circuit is broken. This device consists of a casting 44, which contains bearing 45, into which is journaled the extended end of

motor shaft 42. Mounted on extended end of motor shaft 42 is drum 46, designed to be clamped or released by shoes 47, 48. A solenoid magnet 49, is equipped with two plungers, 50 and 51, attached to levers 52 and 53, which are pivoted at 54 and 55, and control the movement of shoes 47 and 48. The solenoid 49 is wired in parallel with motor 43, so when motor 43 is energized it is entirely free to rotate, but when it is de-energized spring 56 quickly arrests motion of motor shaft by actuating shoes 47 and 48. When armature of motor 43 is rotating, shoes 47 and 48 are held in proper position by resting on projection 57. The assembly on and including casting 44 is attached to bottom of casting 11, by screws 58 and 59. The motor 43 is attached to base 11, by several bolts indicated at 60.

The aye, not-voting and nay circuits of division A are shown at 61, 62 and 63 respectively. Corresponding circuits of division B are shown at 64, 65 and 66 respectively; and said circuits of division C are shown at 67, 68 and 69 respectively. The selector herein illustrated contains only these three voting divisions, but selectors 25 may be built with any desired number of voting divisions.

Although differing in names and recording positions, the voting circuits 61 to 69 inclusively are electrically similar. One diagram would serve to illustrate any circuit from 61 to 69, and such a diagram is shown in Fig. 6.

In Fig. 6 several voting units, 70, 71, 72, 73, 74 and 75 are indicated, and all of them are registering the same kind of vote. Through the several said voting units current from positive battery is shown passing to the several operating contactors 14, which lay in path of wiper end 28b. As wiper ends 28a and 28b are joined together and simultaneously ride over their respective sequences of contactors, impulses of current picked up by wiper end 28b, are transferred to wiper end 28a, and through the operating contactors 14 in its path, over the common conductor 76, to the vote recording solenoids 77 and 45 totalizer vote storing solenoids 78. On occasions when counting is desired without recording, or when continuous totalization is employed, recording solenoids 77 are disconnected by switch blade 79 being thrown from contactor 80 to 50 contactor 81, which places inductance coil 85 in the operating circuit in place of vote recording solenoids 77. The purpose of the inductance coil 85 is to permit the recording circuit to possess the same amount of inductance with the recording solenoids 77 connected or disconnected, so the characteristics of the spark controlling condenser 84 and its retardation coil 83 will not become changed or unbalanced when the vote recording solenoids 77 are disconnected from the 60 circuit.

The same general arrangement of placing inductance coils in circuits when disconnecting operating solenoids therefrom, may also be used in installations where several recorders or totalizers are used but only certain ones of them connected at any one time. With use of such inductance coils recorders or totalizers could be connected or disconnected as desired without influencing the spark control circuits.

It is essential, with vote recording systems using the commutation principle, that the commutator or selector contactors be clean at all times, and that sparking be reduced to a minimum or eliminated altogether. The selector 78

contactors shown herein are therefore designed to have their respective wipers make and break contact with them in open air, and in addition a new and efficient spark control circuit is disclosed.

In a vote recording commutator or selector the wiper must necessarily contact a succession of differing circuits. Fig. 6 shows a method of directly bridging a succession of different circuit contactors with a single condenser, by means of intermediate contactors 13, interspaced between operating contactors 14, and the use of narrow wiper end 28a and wide wiper end 28b. This method of spark control confines activity of condenser 84 to a short isolated local circuit. The width of wiper end 28a is so proportioned, that in conjunction with operating contactors 14 in its path, the desired length of contact is secured for proper operation of vote recording solenoids 17 and totalizer vote storing solenoid 18. Contactors 14 in path of wiper end 28a are connected by conductor 16 to one side of condenser 84. The width of wiper end 28b is so proportioned, that when it is making or breaking contact with any of the operating contactors 14 in its path, it is also bridging one of the intermediate contactors 13, which are joined by conductor 82 to retardation coil 83 and other side of condenser 84. Thus making and breaking of operating current occurs between wiper end 28a and the contactors 14 in its path, and this point is bridged by condenser 84. Obviously wiper end 28b must not be wide enough to bridge together two operating contactors 14, but must be wide enough to overlap a single operating contactor 14 and so establish contact with intermediate contactors 13.

Fig. 7 discloses the electrical theory of the paper feed circuit. Wide wiper end 28b contacts all contactors 13 and 14 in its path. Since wiper end 28b overlaps two contactors at a time and all are joined together by conductor 86, the effect is the same as if a collecting ring was used at this point. Narrow wiper end 28a contacts in turn each operating contactor 14 in its path, which are joined together by conductor 81. The system of spark elimination shown in Fig. 6 is not required here, since the feed circuit of Fig. 7 is only a local circuit. Hence condenser 88 and retardation coil 89 are merely connected with conductors 86 and 87, which shunts them around the make and break occurring between wiper end 28a and the operating contactors 14 in its path. Each time contact is established at this point, feed solenoids 122 operate, and in my preferred construction, feed the record card one step forward each time they are de-energized. When totaling only is desired, without recording, switch blade 90 can be moved from contactor 91 to contactor 92, opening the feed circuit. This switch is preferably automatically controlled.

Fig. 8 discloses the theory of electrical control for the selector driving motor and brake, and the high speed vote counting mechanism. In this figure the devices indicated as continuous collecting rings, or portions thereof, are, in actual practice, constructed like the left hand view in Fig. 7—that is, by connecting all contactors together, and sweeping them with a wide wiper end such as 28b. In Fig. 8 current from positive battery and over conductors 93 and 94, passes through brake release solenoid 49 and selector driving motor 43, to negative lead 85, whenever push button switch 96 is closed momentarily or switch blade 97 is moved from contactor 98 to contactor 99. When momentary switch 96 is

closed current from solenoid 49 and motor 43 passes over contactor 100, through wiper ends 28b and 28a, and contactor 101 to negative 85. By time finger is removed from momentary switch 96, wiper 28a is contacting contactor 102, which keeps solenoid 49 and motor 43 energized until wiper 28a completes a full turn and runs off contactor 102. When switch blade 97 is moved to contactor 99 for continuous totalization, current from solenoid 49 and motor 43 is conducted over wire 103 to negative 85. When switch blade 97 is restored to contactor 98, solenoid 49 and motor 43 continue to be energized until wiper 28a runs off contactor 102. A suitable condenser 104 and retardation coil 105 are bridged across wiper 28a and contactor 102 so that any spark caused by opening of circuit through solenoid 49 and motor 43 may be controlled.

In Fig. 8, a switch, actually of the automatically controlled type, is indicated by blade 106 and contactor 107, and when this switch is closed the total registering and displaying mechanism is operative. The magnets T1 cause the films or equivalent to be moved forward to register all first, or A, division votes. The magnets T2 cause the films or equivalent to be moved forward to register all second, or B, division votes. The magnets T3 cause the films or equivalent to be moved forward to register all third, or C, division votes. The magnets d lock and center the mechanism for moving forward the films or equivalent, before, between and after said movements forward. The lamps e are projection lamps for displaying the totals. It must be remembered that instead of film or some equivalent thereof, it is also possible to use number wheels, or discs, or drums, for indicating or printing the totals, whenever this form of total registration is preferred. The magnets d, T1, T2, T3, and lamp e, shown at 8a, are for registering the aye vote. Those shown at 8b are for registering the not-voting vote. Those shown at 8c are for registering the nay vote.

The lamps e light when switch 106—107 is closed, and then are controlled by wipers 28a and 28b riding on contactors 108 and 109 respectively, which are bridged by condenser 110 and retardation coil 111 for spark prevention purposes. For single totals, lamps e light, displaying zero totals for half a cycle, are dark for half a cycle while totals are being set up, and then display final totals. For continuous totalization lamps e are on for half a cycle and off for half a cycle, showing a new total every time they are re-illuminated. Final totals are displayed in both cases until switch 106—107 is opened.

In Fig. 8, locking magnets d, and divisional total registering magnets T1, T2 and T3 are controlled by switch 106—107 and by wide wiper 28b riding on contactor 112, and narrow wiper 28a contacting the series of contactors illustrated. Contactors in path of wiper 28a that are connected with conductor 113, control magnets d. The individual contactors in path of wiper 28a that are connected respectively with conductors 114, 115 and 116, control divisional total registering magnets T1, T2 and T3. Retardation coil 134 and condenser 135 bridge the principal break occurring at this point.

Fig. 9 shows at 117 a section of one of the insulating rings 12. Recesses 118 and 119 accommodate contactors such as 14 and 18 respectively, while tie-rod holes are indicated at 120. The advantage of ring-sections is that they may be die cast from suitable insulating compounds, elim-

inating the expensive machining of solid rings.

Fig. 10 is a diagram illustrating theory of selector operation through one complete cycle. Wiper 121 is resting on stop-start contactor 101 5 ready for a starting impulse. When such impulse is received wiper 121 contacts contactor 102 and thereby continues to revolve until wiper 121 runs off contactor 102. For approximately three quarters of this cycle votes are being recorded and 10 stored for counting as indicated by wiper 121, riding on contactor 123. Then wiper 121 leaves 123, locks and centers the total registering mechanism at 124, registers first division totals at 125, locks and centers at 126, registers second division totals at 127, locks and centers at 128, registers 15 third division or final totals at 129, locks and centers them in position at 130 and at the same time displays them by projection lamps lighting as indicated by wiper 121 contacting contactor 20 131. When only a single record or count is made, current is removed from the vote registering circuits by opening of switch 106-107 after the selector has completed its cycle of operation, which automatically extinguishes projection 25 lamps and permits the films or equivalents to return to their normal or zero position.

With continuous totalization, wherein new totals are displayed each cycle, the old totals are locked and centered in position as long as wiper 30 121 is riding contactor 130, and said old totals are projected or displayed as long as wiper 121 is riding contactor 131. When wiper 121 leaves contactors 130 and 131 current is removed from the vote registering circuits for a period indicated 35 by the arrow-headed line 132, whereupon the films or equivalents are returned to their normal or zero position while the projection lamps are extinguished. After old totals are reset in space 132 new totals are set up and locked and centered 40 in position by contactors 124 to 130 inclusively, and as the final totals are locked in position they are displayed by wiper 121 contacting contactor 131.

As films or their equivalents are automatically 45 reset after completion of each vote by removal of current from vote registering circuits, it is evident that when system is turned on for taking a new vote, zero totals will be displayed until operation of the selector causes new totals to be shown. 50 This may also be seen from the fact that wiper 121 contacts contactors 130 and 131 in its normal position, so these circuits are established when current is turned on.

While wiper 121 is riding contactor 123 and so 55 recording and storing the vote, said wiper is also riding contactor 133 which causes the record card to be fed through the recorder. As indicated by dotted line extension to contactor 133, the feed impulses may continue past the final recording 60 impulses, so the card may be fed entirely out of the recorder. This is necessary especially when record cards are printed on a roll of tape.

What I claim as new and desire to secure by Letters Patent of the United States is as follows:

65 1. A selector comprising a base member having a recessed housing therein, a multiplicity of superimposed insulating ring members, an end member, means extending through said end member and through each of said superimposed insulated ring members and into the recessed housing of said base member for assembling said ring members in position to form a substantially cylindrical insulated housing, a multiplicity of contact members supported by said ring members and 70 projecting radially inward within said housing,

a rotary shaft member journaled between the recessed housing of said base member and said end member, a wiper rack carried by said rotary shaft, a plurality of contact wipers supported by said wiper rack for establishing wiping electrical connection with said contact members as said shaft is rotated, and means mounted within the recessed housing of said base member for positively controlling said shaft member. 5

2. A selector comprising a base member having a recessed housing therein, a multiplicity of superimposed insulated ring members, an end member, means extending through said end member and through each of said superimposed insulated ring members and into the recessed housing of said base member for assembling said ring members in position to form a substantially cylindrical insulated housing, a multiplicity of contact members supported by said ring members and projecting radially inward within said housing, a rotary shaft member journaled between the recessed housing of said base member and said end member, a plurality of contact wipers supported by said shaft member and coating with the contact members supported by said ring members for establishing successive connection with the contact members as said shaft member is rotated, and means mounted within the recessed housing of said base member for positively controlling said shaft member. 15 20 25

3. A selector comprising an end member, a plurality of superimposed insulated ring members supported adjacent said end member, an opposite end member disposed adjacent the opposite end of the group of insulated ring members, means extending between each of said end members for maintaining said ring members in superimposed relation, a rotatable shaft journaled in said end members, means carried by one of said end members for positively controlling said shaft, a multiplicity of contact members carried by said insulated ring members and projecting radially inward toward said shaft member, and a plurality of contact wipers supported by said shaft member and operative to establish successive electrical connection with the coating contact members as said shaft is rotated. 30 35 40 45

4. A selector comprising an end member, a plurality of superimposed insulated ring members supported adjacent said end member, an opposite end member disposed adjacent the opposite end of the group of insulated ring members, means extending between each of said end members for maintaining said ring members in superimposed relation, a rotatable shaft journaled in said end members, means carried by one of said end members for positively controlling said shaft, a multiplicity of contact members carried by said insulated ring members and projecting radially inward toward said shaft member, a plurality of contact wipers supported by said shaft member and operative to establish successive electrical connection with the coating contact members as said shaft is rotated, and a housing engaged with one of said end members and secured to the other of said end members for substantially enclosing all of said ring members, the contact members carried thereby and the controlling means for said shaft member. 50 55 60 65 70

5. A selector comprising an end member, a plurality of superimposed insulated ring members supported adjacent said end member, an opposite end member disposed adjacent the opposite end of the group of insulated ring members, means extending between each of said end mem- 75

bers for maintaining said ring members in superimposed relation, a rotatable shaft journaled in said end members, means carried by one of said end members for positively controlling said shaft, a multiplicity of contact members carried by said insulated ring members and projecting radially inward toward said shaft member, a plurality of contact wipers supported by said shaft member and operative to establish successive electrical connection with the coacting contact members as said shaft is rotated, a flange formed on one of said end members, a screw threaded extension formed on the other of said end members, and a housing wholly enclosing said ring members and the contacts carried thereby, said housing engaging the flange on one of said end members and being secured over the screw threaded extension on the other of said end members.

6. A selector comprising supporting means, a plurality of insulated ring members carried by said supporting means, an end member disposed adjacent the end of the group of insulated rings, means interconnecting said supporting means and said end member for maintaining said insulated rings in superimposed relation, a rotatable shaft journaled between said supporting means and said end member, contact members carried by said insulated ring members and projecting radially inwardly, contact wipers supported by said shaft member for establishing successive electrical connection with coacting contact members as said shaft member is rotatably driven, means for adjusting the transverse relationship of said contact wipers for predetermining the relative time at which connection is established and broken between certain of said contact wipers and certain of said contact members, and means for positively controlling said shaft member.

7. A selector comprising supporting means, a plurality of insulated ring members carried by said supporting means, an end member disposed adjacent the end of the group of insulated rings, means interconnecting said supporting means and said end member for maintaining said insulated rings in superimposed relation, a rotatable shaft journaled between said supporting means and said end member, contact members carried by said insulated ring members and projecting radially inwardly, an insulated rack carried by said shaft member and extending longitudinally through said ring members, a plurality of con-

tact wipers, and means for mounting said contact wipers on said insulated rack and selectively adjusting the transverse position thereof for predetermining the relative time at which connection is made and broken with the coacting contact members as said shaft member is rotated, and means for positively controlling said shaft member.

8. Selector switch structure comprising an insulated support, a plurality of pairs of fixed contactors mounted in said support with the contactors of each pair in superposed spaced relation, a U-shaped conductive member insulatingly mounted at the base thereof with the arm portions of said member disposed in spaced relation for contacting the contactors of each said pair of fixed contactors, the arm portions of said member comprising separate wipers of different widths, a corresponding plurality of fixed auxiliary contactors mounted in said support intermediate the contactors engageable by the wiper of greater width, and means for moving said U-shaped conductive member for selectively contacting each pair of fixed contactors in bridging relation and said intermediate auxiliary contactors in parallel relation with the respective adjacent contactors of said pairs.

9. Selector switch structure comprising an insulated support, a plurality of pairs of fixed contactors mounted in said support with the contactors of each pair in superposed spaced relation in air, a movable contactor comprising two coacting U-shaped conductive members insulatingly mounted at the bases thereof with the respective arm portions of said members contiguously disposed and coacting to provide wiper clips in spaced relation for engaging the contactors of each said pair of fixed contactors in air, and means for moving said movable contactor for selectively contacting each pair of fixed contactors in bridging relation.

10. Selector switch structure as set forth in claim 9 and including a corresponding plurality of fixed auxiliary contactors mounted in said support intermediate the contactors of said pairs engageable by one of said wiper clips, the said one of the clips having a longer wiping contact portion than the other of said clips for selectively contacting said intermediate auxiliary contactors in parallel relation to the respective adjacent contactors of said pairs.

CHARLES F. THOMPSON.
